An ornamental design for a privacy gown, as shown and described.

DESCRIPTION

FIG. 1 is a front perspective view of a new design for privacy gown having a front pocket located beneath the lower arm opening of a sleeve including a skirt and strap in proximity.

FIG. 2 is a front view thereof; showing symmetrical fasteners on either side of a shoulder portion of the privacy gown
FIG. 3 is a rear view thereof; showing symmetrical fasteners on either side of a waist portion of the privacy gown located beneath a lower opening of each sleeve.

FIG. 4 is a left side view thereof; showing linear alignment of a shoulder fastener and a waist fastener relative to a left side seam;

FIG. 5 is a right side view thereof; showing linear alignment of another shoulder fastener and another waist fastener relative to a right side seam;

FIG. 6 is a top view thereof; showing a diamond shaped V-neck opening between a front portion and a rear portion of the privacy gown; and,

FIG. 7 is a bottom view thereof.
The solid line showing illustrates the claimed features within the design for the claimed article of manufacture. The shading is provided to illustrate contour only and is not an indication of texture, gloss, etc.

The broken lines shown illustrate stitching of the privacy gown that forms no part of the claimed design.
